(57) **CLAIM**

The ornamental design for a battery pack with a keying flat,
as shown and described.

DESCRIPTION

FIG. 1 is a first perspective view of a battery pack with a
keying flat according to a first embodiment.

FIG. 2 is a second perspective view of the battery pack with
a keying flat of FIG. 1.

FIG. 3 is a third perspective view of the battery pack with
a keying flat of FIG. 1.

FIG. 4 is a left side view of the battery pack with a keying
flat of FIG. 1.

FIG. 5 is a right side view of the battery pack with a keying
flat of FIG. 1.

FIG. 6 a front side view of the battery pack with a keying flat
of FIG. 1.

FIG. 7 is a top side view of the battery pack with a keying
flat of FIG. 1.

FIG. 8 is a first perspective view of a battery pack with a
keying flat according to a second embodiment.

FIG. 9 is a second perspective view of the battery pack with
a keying flat of FIG. 8.

FIG. 10 is a third perspective view of the battery pack with
a keying flat of FIG. 8.

FIG. 11 is a left side view of the battery pack with a keying
flat of FIG. 8.

FIG. 12 is a right side view of the battery pack with a keying
flat of FIG. 8.

FIG. 13 a front side view of the battery pack with a keying
flat of FIG. 8; and,

FIG. 14 is a top side view of the battery pack with a keying
flat of FIG. 8.

The evenly spaced dashed broken lines depict portions of the
battery pack with a keying flat that form no part of the
claimed design. The dot-dash broken lines depict the bounds
of the claim and form no part of the claimed design.
